UNITED STATES PATENT OFFICE.

HUGO LENTZ, OF BERLIN-HALENSEE, GERMANY.

STEAM-ENGINE FOR LOCOMOTIVES.

1,925,842.

Specification of Letters Patent.

Patented May 8, 1917.

Application filed January 6, 1915, Serial No. 717. Renewed October 2, 1916. Serial No. 123,447.

To all whom it may concern:

Be it known that I, HUGO LENTZ, a citizen of the German Empire, and resident of Berlin-Halensee, Germany, have invented certain new and useful Improvements in Steam-Engines for Locomotives, of which the following is a specification.

My invention relates to improvements in steam engines for locomotives, and the object 10 of the improvements is to provide an engine of this class in which the steam cylinder and the steam chest consist of a casting of simple form which can be made at comparatively low cost, and in which the steam cylinder and its supporting plate or saddle can readily be secured to the frame work of the locomotive. A further object of the improvements is to construct the cylinder and steam chest in such a way, that there is no 15 transmission of heat between the steam chambers, so that the said chambers are insulated from each other. Finally an object of the improvements is to provide a steam cylinder in which the shaft controlling the 20 valves is perfectly free of steam pressure acting in one direction, so that the said shaft can easily be mounted on the steam chest and special means for tightening the same as against the walls of the steam chest are not necessary. With these and other objects in 25 view my invention consists in constructing the steam cylinder, its supporting plate or saddle, and the steam chest in such a way, that the cylinder which is disposed at a distance from the supporting plate or saddle and the chest inclosing the shaft controlling the 30 valves and the steam admission and exhaust chambers are disposed separately of the cylinder, said chambers being provided 35 around the casing inclosing said shaft. Furthermore the exhaust chamber and the casing communicate with each other, so that the 40 pressures acting on the said shaft are in equilibrium.

For the purpose of explaining the invention an example embodying the same has been shown in the accompanying drawing, in which the same letters of reference have been used in all the views to indicate corresponding parts. In said drawing—

Figure 1, is a longitudinal section of the steam cylinder and associated parts, the left hand part of the figure being a section taken on the line I—I of Fig. 2, and the right hand part of the figure being a section taken on the line I'—I' of Fig. 2, and

Fig. 2, is a cross-section taken on the line II—II of Fig. 1.

Referring to the example illustrated in the drawing, the steam cylinder 2, its supporting plate or saddle 1, and the valve chest 4 consist of an integral casting. The supporting plate 1 is adapted to be secured to the frame of a locomotive by screw bolts or the like, and it is formed with ribs 3 which are 60 made integral with the steam cylinder 2, the latter being disposed at a distance from the supporting plate. Above the steam cylinder 2 and perfectly separate therefrom and cast integral with the supporting plate 1 the casing 4 is provided which receives a shaft 22 controlling admission and exhaust valves 7 and 15, and the bore of the said casing is perpendicular to the supporting plate 1 and a plane passing through the axis of the 70 cylinder.

Above the casing 4 and at the side which is away from the supporting plate 1 a steam admission chamber 5 is formed to which live steam is admitted through a short pipe 6. 80 The live steam chamber 5 communicates through ports 8 controlled by the admission valves 7 with passages 16 connected with the hollow of the cylinder at opposite ends thereof, as is shown at the left in Fig. 1. 85 The admission valves which are formed with two faces are acted upon by springs 9 and secured to stems 10 which are guided in a steam tight manner in bushings 11 formed with annular grooves. The bushings are 90 fitted within the bores of cylindrical parts 26 providing guides for the valve shafts, which bores end perpendicularly in the casing 4 of the shaft 22. The cylindrical parts 26 are disposed perfectly independently of the 95 walls of the live steam chamber 5 and below the same, so that transmission of heat can not take place.

At the side of the live steam chamber 5 the exhaust steam chamber 13 is provided 100 which is located around the casing 4 of the valve shaft and extends over the whole length of the cylinder. It is formed with a pipe 14 to which the exhaust steam pipe is connected. The live steam chamber and the 105 exhaust steam chamber are perfectly separate from each other, so that transmission of heat cannot take place. The ends of the exhaust steam chamber 13 communicate through ports 25 controlled by the exhaust valves 15 with the passages 16. The exhaust valves are formed with two faces, and 110

they are acted upon by springs 17 and secured to stems 18 which are mounted in a tight manner within the bushings 19 formed with annular grooves. At their outer ends 5 the said bushings are formed with flanges 19' which provide one of the seats of the exhaust valves. The bushings 19 are fitted in bores of cylindrical parts 20 which end perpendicularly in the casing 4 of the shaft 10 of the valve gearing. The casing 4 and the exhaust chamber 13 are always in communication with each other through a bore 21. Thereby any steam which might pass along 15 the valve stems 10 and 18 is removed, and simultaneously the pressures acting on the valve shaft 22 are balanced, so that special tightening means are not necessary for this shaft. By means of the valve gearing rocking movement is imparted to the valve shaft, 20 as is known in the art, and the valve shaft is formed with cams 23 and 24 for operating respectively the admission and exhaust 25 valves 7 and 15.

By constructing the steam cylinder and 25 the parts associated therewith in the manner described a-casting is obtained which is simple in form and can easily be manufactured. The casting can readily be secured to the frame of the locomotive, and ready 30 access can always be had to the screw bolts provided for this purpose. The cylinder is freely supported by the ribs 3 and it is connected with the casing inclosing the valve 35 shaft and the steam chambers exclusively through the walls of the passages 16, this connection being such that any transmission of heat between the steam chambers is avoided and the parts of the cylinder are insulated from one another in the most simple 40 way. This is particularly important in steam engines for locomotives which are driven by superheated steam.

By connecting the casing inclosing the valve shaft with the exhaust chamber the 45 valve chamber is released from pressure acting in one direction, so that the said valve shaft can easily be mounted and special tightening means are not necessary.

I claim herein as my invention:

50 1. In a steam engine for locomotives and the like, the combination with a supporting plate, of a steam cylinder disposed at a distance from the supporting plate, valves and means including a shaft for operating the same, and a casing providing a support for the valve shaft, said casing being disposed independently of the cylinder and

having steam admission and exhaust chambers arranged about the same and independently of the cylinder. 60

2. In a steam engine for locomotives and the like, the combination with a supporting plate, of a steam cylinder disposed at a distance from the supporting plate, valves and means including a shaft for operating 65 the same, and a casing providing a support for the valve shaft, said casing being disposed independently of the cylinder and having steam and exhaust chambers arranged about the same and independently 70 of the cylinder and each other.

3. In a steam engine for locomotives and the like, the combination with a supporting plate, of a steam cylinder disposed at a distance from the supporting plate, valves and 75 means including a shaft for operating the same, a casing providing a support for the valve shaft, said casing being disposed independently of the cylinder, and at least one chest surrounding the casing of the valve 80 shaft and having its inner wall at a distance from the casing and providing admission and exhaust chambers.

4. In a steam engine for locomotives and the like, the combination with a supporting 85 plate, of a steam cylinder disposed at a distance from the supporting plate, valves and means including a shaft for operating the same, a casing providing a support for the valve shaft, said casing being disposed independently of the cylinder, and admission 90 and exhaust chests surrounding said casing and disposed with their inner walls at a distance from the casing.

5. In a steam engine for locomotives and 95 the like, the combination with a supporting plate, of a steam cylinder disposed at a distance from the supporting plate, valves and means including a shaft for operating the same, and a casing providing a support for 100 the valve shaft, said casing being disposed independently of the cylinder and having steam admission and exhaust chambers arranged about the same and independently of the cylinder, said casing communicating 105 with the exhaust chamber.

In testimony whereof, I have signed this specification in the presence of two subscribing witnesses.

HUGO LENTZ.
